Moses Brucklin
Letter Patent

The subscriber of and in these Letters Patent and making part of the same containing a description in the words of the said Moses Brucklin himself of his improvement in the construction of Water Pumps

To all to whom these presents shall come. Be it known that Moses Brucklin of Crafston in the County of Crafston & State of New Hampshire has invented a new & useful improvement in the construction of water pumps & that the following is a full & exact description of the construction & operation of the said machine as invented or improved by me viz. A log or stock is prepared in the usual form of common suction pumps of length proportioned to the depth of the well, this being bored thro' & rimmed from the top nearly to the bottom is prepared for a lining or chamber to be of lead composition or other metal contracted at the bottom to the form of the rimmed end in having the log or log of pipe intended to be used. A piece of lead pipe is then soldered to this chamber & cutted at the top or upper end of the log and thro' at the bottom so as then to be brought down with a quick & smart motion which will shape it to the rimming of the log & make it tight. In this chamber or lining the tops are placed & are in the usual form. The log or stock is now fitted for setting up which may be over the well or at a distance from it as the owner wishes. When water is to be drawn a considerable distance a great improvement consists in making a vacuum or air receiver in the pipe near the pump. This is made of white oak or other suitable timber in the shape of a key without a bidge & have a piece of pipe fixed in each end & near the ultimate end to go down it is then to be covered with sheet lead perfectly tight. The pipe is joined a few feet from the pump with that in the pipe & then the opposite end extended to the well. The said Brucklin claims as an improvement in said pump the lining and chamber & the pipe soldered to it thereby preventing all liability of leaking & making said machine of wood & iron.
